IRONING MACHINE

Lewis Barnes, New York, N. Y.

Application September 29, 1953, Serial No. 383,020

1 Claim. (Cl. 38—59)

This invention relates to ironing machines of the type having a padded roller mounted on a stand and positioned to coat with a heated shoe or buck, and in particular an ironing machine having three primary movements with the roller adapted to oscillate about its axis, rotate, and slide longitudinally whereby a plurality of ironing actions are obtained which make it possible to iron materials with substantially the same movements produced in hand ironing.

The purpose of this invention is to provide a universal ironing machine in which reciprocating movements are combined with rotary travel of a roll and in which substantially all types of materials and garments may be ironed thereby.

Ironing elements of ironing machines have been provided of various types and designs to compensate for different materials and articles to be ironed thereon and to imitate ironing by hand, however, it has been found difficult to combine the rotary and sliding movements where the sliding movements are both transversely and longitudinally disposed.

With this thought in mind this invention contemplates an ironing machine having a roller mounted on an elongated spindle with the roller positioned to coat with a heated buck or shoe and in which operating means are provided for elevating and lowering the buck, for oscillating the roller with transversely disposed movements, for rotating the roller continuously, and also for sliding the roller longitudinally on the spindle and in relation to the buck.

The object of this invention is, therefore, to provide means for forming a combination or universal ironing machine in which a roller journaled on a spindle is rotated, and reciprocated transversely and longitudinally and in which a buck, mounted to coat with the roller, is adapted to be raised and lowered to compensate for different materials or articles being ironed.

Another object of the invention is to provide means in an ironing machine whereby an ironing roller is adapted to be reciprocated transversely, reciprocated longitudinally or rotated continuously in which the different movements are controlled by cams and in which the cams are, selectively, actuated by clutches.

A further object of the invention is to provide a universal ironing machine in which the ironing roller is reciprocated transversely, rotated continuously, or reciprocated longitudinally and in which the heated shoe or buck is adapted to be raised and lowered, in which the machine is of a comparatively simple and inexpensive construction.

With these and other objects and advantages in view the invention embodies a vertically disposed stand having a spindle journaled in the upper part and extended from one end thereof, a padded roller mounted to slide longitudinally and rotate on said spindle, a heated buck positioned above the roller, foot actuated means for elevating and lowering the buck, and a plurality of cam actuated clutches for engaging and disengaging operating devices for selectively actuating the different parts of the ironer.

2

Other features and advantages of the invention will appear from the following description taken in connection with the drawings, wherein:

Figure 1 is a front elevational view showing the general design and arrangement of the improved ironer.

Figure 2 is a longitudinal section through the ironer with the front plate of the housing omitted and showing in particular the position of the cams and clutches with the parts adapted to reciprocate the roller transversely.

Figure 3 is a plan view of the ironer.

Figure 4 is a longitudinal section similar to that shown in Fig. 2 with the parts shown on an enlarged scale and with the parts also shown in the position of reciprocating the roller transversely.

Figure 5 is a cross section through the end of the ironer housing taken on line 5—5 of Fig. 4.

Figure 6 is a similar section taken on line 6—6 of Fig. 4 illustrating the relative positions of the clutch and cam carrying shafts.

Figure 7 is a cross section taken on line 7—7 of Fig. 4 also showing the relative positions of the shaft and spindle.

Figure 8 is a cross section taken on line 8—8 of Fig. 4 showing the arm for reciprocating the roller longitudinally.

Figure 9 is a cross section taken on line 9—9 of Fig. 4 showing the relative positions of the spindle and lower operating shaft.

Figure 10 is a cross section taken on line 10—10 of Fig. 1 showing the ironing buck in a slightly elevated position in relation to the roller.

Figure 11 is a similar section taken on line 11—11 of Fig. 1 also showing the relative positions of the ironing roller and buck.

Figure 12 is a detail showing a front elevational view of the ironing buck and operating elements thereof and with parts of the ironing machine broken away.

Figure 13 is a detail showing a section through the heated shoe or buck taken substantially on line 11—11 of Fig. 1 illustrating the interior construction of the buck and showing the device mounted on the upper end of a post, with other parts broken away.

Figure 14 is a longitudinal section through the buck also with parts broken away.

Figure 15 is a detail illustrating one of the clamps for mounting the clutch operated elements on the frame of the machine.

Figure 16 is a cross section through the clamp taken on line 16—16 of Fig. 15.

Figure 17 is a detail illustrating the cam groove for actuating the clutch for reciprocating the roller transversely.

Figure 18 is a similar view showing the cam groove for actuating the clutch through which the roller is rotated in a clockwise direction.

Figure 19 is a similar detail illustrating the groove of the cam for actuating the clutch for reciprocating the roller longitudinally.

Figure 20 is an end elevational view of one of the cams illustrating the relative positions of the slots or grooves therein.

Figure 21 is a similar view with the cam shown on an enlarged scale illustrating the relative positions of high points of the cam grooves.

Figure 22 is a detail showing a section through one of the terminals of the buck illustrating the method of connecting electric supply circuits to the heating elements thereof.

Referring now to the drawings wherein like reference characters denote corresponding parts, the ironing machine of this invention includes a roller 10 mounted on a spindle 11 with a sleeve 12 slidably mounted on the spindle and forming the core of the roller, a shoe 13 hav-

ing an arcuate under surface 14 and having electric heating elements 15 and 16 therein, a post 17 on the upper end of which the shoe is mounted with an arm 18, and a plurality of cams and clutches mounted in the upper portion of a housing mounted on wheels or rollers 19 and having a base 20.

The roller 10 is formed with a fabric cover, to which the numeral 10 refers, positioned on a cylinder or casing 21 and, as illustrated in Fig. 4, the cylinder is provided with spiders having bands 22 supported from hubs 23 with spokes 24, the spiders being positioned in the ends, and the spider at the inner end being rotated against a collar 25 on the sleeve 12.

The cylinder 21 is secured to the bands 22 of the spiders with set screws 2 and the collars 25 are secured in position on the sleeve 12 with set screws 5.

The ironing machine has four cams, three of these cams being used to shift the position of the rotors. The cam at 38 is designated as the horizontal oscillation rotor cam. The cam 38 is provided with a groove 37 which is engaged by a projection 36 on the arm 26 that is clamped to the sleeve 12 that is slidably mounted on the spindle 11 for the roller 10. The cam at 104 is designated as the vertical oscillation positioning cam. The cam 104 is provided with a groove 107 which is engaged by the projection 108 of a slider 109. The cam at 96 is designated as the vertical clockwise positioning cam. The cam 96 is provided with a groove 95 which is engaged by a projection 94 of a slider 93. The cam 71 is designated as the horizontal oscillation positioning cam. The cam 71 is provided with a groove 70 that is engaged by a projection 69 on a plate 67 that is attached to the slider 65. The projections on the sliders engage their respective grooves in their respective cams as set forth to effect the operation of the various rollers, as will be later described.

As illustrated in Figs. 8 and 9 an arm or lever 26 is clamped on the sleeve 12 between the collar 25 and a similar collar 27 with the portion of the sleeve positioned between the collars clamped in an arcuate section 28 of the arm 26 with a complementary arcuate section 29 having a base 30 and positioned in a recess 31 of the arm and having a flange 32 extended from the opposite end. The flange 32 is secured by bolts 33 to a flange 34 on the upper end of the arm 26 and the base 30 is secured to the arm 26 with bolts 35. The lower end of the arm 26 is provided with a projection 36 that extends into a groove 37 in a cam 38 on a shaft 39 journaled in vertically disposed members 40 and 41 of an inner frame, with bearings 42 and 43.

The supporting frame, of which the members 40 and 41 form parts is provided with additional vertically disposed members 44 and 45 which are mounted on a base 46 and, as shown in Fig. 4 the upper ends of the members are connected with a horizontal member 47. The frame is also provided with an upper intermediate member 48, a lower member 49 extended between the members 41 and 44 and a connecting member 50 by which the member 40 is mounted on the member 41.

Upon rotation of the cam 38 from the position shown in Fig. 4, the projection 36 on the lower end of the arm 26 follows the groove 37 whereby the arm 26 moves outwardly carrying the ironing roller 10 and sleeve 12 longitudinally of the spindle 11 whereby upon continued rotation of the cam 38 the roll 10 reciprocates longitudinally.

The cam 38 is mounted on a sleeve 51, to which the sleeve is secured with a set screw 52 and, as shown in Fig. 4, the extended end of the sleeve 51 is provided with a jaw 53 of a clutch having a coacting jaw 54. The jaw 54 is carried on one end of a sleeve 55 on the opposite end of which a clutch collar 56 is mounted, the clutch collar being held against the flange 57 with a spring 58.

The arm 26 is also provided with a guide bar 59 that extends through a U-shaped bracket 60 that is secured to the frame member 40 with bolts 61. The end wall 62 of

the housing is provided with an opening 63 through which the bar 59 may extend.

The clutch collar 56 is actuated by a yoke 64 extended upwardly from a slider 65 mounted on the member 49, as illustrated in Figs. 15 and 16, the slider 65 extending over the upper surface of the member 49 and having a flange 66 extended over the member; and the slider being secured on the member with a bottom plate 67 that is attached to the slider with screws 68. The plate 67 is provided with a projection 69 that extends into a cam groove 70 of a cam 71 and the cam 71 is mounted on a shaft 72 which is journaled in the frame members 41 and 44 with bearings 73 and 74, respectively.

The shaft 39 is rotated by a motor 75 through an endless belt 76 that is trained over a pulley 77 on the motor shaft and a pulley 78 on the shaft 39, and the shaft 11 is rotated from the shaft 39 with a chain 79 that is trained over a sprocket 80 on the shaft 39 and the sprocket 81 on the shaft 11. The sprocket 81 is secured to a sleeve 82 with a set screw 83 and, as shown in Fig. 4, the sleeve 82 is provided with a clutch jaw 84 that coacts with a similar jaw 85 on a sleeve 86 on the opposite end of which is a flange 88 against which a clutch collar 89 is held with a spring 90. The sleeve 86 is keyed to the shaft with a key 91 and the clutch collar 89 is actuated by a yoke 92 extended from a slider 93 slidably mounted on a member 48 and having a projection 94 extended from the lower side which extends into a groove 95 of a cam 96 on a shaft 97.

The shaft 97 is rotated from the shaft 72 with an endless chain 98 that is trained over a sprocket 99 on the shaft 97 and over a sprocket 100 on the shaft 72.

The extended end of the shaft 72 is provided with an index wheel or pointer 101 by which the shaft, with the cam 71 thereon, may be rotated until the projection 69 is in the high point 102 of the cam slot at which time the slider 65 is moved on the member 49 until the jaw 53 of the clutch is in engagement with the jaw 52 so that with the jaw 53 secured to the shaft 39 with a key 103 the cam 38 will be rotated, moving the projection 36 longitudinally with a reciprocating action whereby the arm 26 longitudinally reciprocates the ironing roller 10.

At the same time the chain 98 rotates the shaft 97, turning the cam 96, and also turning a cam 104 positioned on the opposite end of the shaft.

With the cams 71, 96, and 104 adapted to be rotated by the lever or index wheel 101 these cams are adapted to be set so that the high point of each cam groove may be positioned to close its respective clutch, whereby the different movements of the machine are independently controlled.

By this means a high point 105 of the cam groove 95 of the cam 96 is adapted to be set to close the clutch jaws 84 and 85 whereby the shaft 11 will rotate in a clockwise direction continuously so that ironing may be continued in the conventional manner.

At the same time the movement of the member 101 may be continued to the position illustrated in Fig. 4 in which position the high point 106 of the cam groove 107 of the cam 104 holds the projection 108 of a slider 109 on the member 48 whereby a clutch jaw 110 is in engagement with a clutch jaw 111 on the inner end of a sleeve 112 on the end of the shaft 11. With the jaws 110 and 111 in engagement and with a sleeve 113 on which the jaw 110 is positioned keyed to the shaft 11 with a key 114 the shaft 11 with the roller 10 will be reciprocated transversely.

The sleeve 113 is provided with a clutch collar 115 that is urged against a flange 116 by a spring 117, and the collar 115 is actuated by a yoke 118 extended from the slider 109.

As illustrated in Figs. 4 and 5 the sleeve 112 is provided with a lever 119 that is secured to the sleeve with a set screw 120 in a hub 121 and the lower end of the lever is connected to a link 122 with a pin 123. The

opposite end of the link 122 is pivotally connected by a pin 124 to the end of an arm 125 that is secured to the shaft 39 with a set screw 126 in a hub 127 of the arm. With the parts mounted as illustrated in Fig. 5 rotation of the shaft 39 carries the arm 125 around a circle with the link 122 moving the lower end of the lever 119 from the position shown in full lines to the position shown in dotted lines whereby the shaft 11 is turned to an angle of substantially 30 degrees. With the parts moving continuously from the position shown in full lines to the position shown in dotted lines and from the position shown in dotted lines back to the position shown in full lines the shaft 11 oscillates or reciprocates transversely.

With the sprocket 81 mounted on the sleeve 82 the sprocket and sleeve are free to rotate with the shaft 39 as the motor is in operation and a rotary motion is transmitted to the shaft 11 when the jaws 84 and 85 are in engagement. By the same means the shaft 11 is reciprocated transversely or oscillated when the jaws 110 and 111 of the clutch actuated by the cam 104 are in engagement, as shown in Fig. 4.

The inner frame in which the cam and clutch shafts are mounted is positioned in an upper compartment or section of a housing forming the stand of the ironer with the base 46 of the frame positioned on a base 130 and with the upper portion of the frame supported laterally by threaded studs 131 and 132, the upper ends of which are threaded into an upper plate 133 and the lower ends of which are threaded into the upper member 47 of the frame. The end plate 62 is provided in one end of the upper section of the housing and the plate 134 is provided at the opposite end. The housing is also provided with a rear plate 135 and a front plate 136 in which a door 137 is provided, as shown in Fig. 1. The door 137 is secured to the plate 136 with hinges 138 and 139 and a latch 140. The plate 138 is secured to the side and end plates of the housing with screws 141. The plate 62 is provided with an offset section having a horizontally disposed portion 142 and a vertical section 143 and, as shown in Fig. 4, the portion 142 is provided with a slot 144 in which the arm 26 travels.

The plate 62 is also provided with a projection or indicator 145 that is positioned to coact with the lever or index wheel 101 to show which cam is in the operative position or in positions wherein the clutches are engaged or disengaged.

The ironer housing or stand is also provided with a lower back plate 146, end webs 147 and 148 and an intermediate web 149. These parts are mounted on the base 20 and extend upwardly therefrom and, as shown in Figs. 1, 10, 11, and 12 the buck or shoe 13, which is carried by the arm 18 extended from the post 17 is mounted on the rear plate 146. The post 17 is slidably mounted or telescopes in a tubular section 150 and the post is secured in adjusted positions with a set screw 151 in a collar 152 on a mounting plate 153.

The lower end of the post 17 is provided with a foot plate 154 that extends forwardly, as shown in Figs. 10 and 11, so that it is within reach of a foot of the operator whereby the shoe may be held downwardly upon the ironing roll 10 as the machine is in operation.

A foot crank 155 is provided for elevating the shoe and, as illustrated in Figs. 1 and 12 the crank 155 is pivotally mounted by a pin 156 in spaced vertically disposed bars 157 and 158 and, as illustrated in Fig. 12, the post is elevated by placing a foot on a pedal 159 and pressing the upper end of the lever downwardly, as shown in dotted lines whereby a roller 160 in the opposite end of the lever presses upwardly against the under surface of the foot plate 154. With the post and shoe in the elevated position a latch 161, pivotally mounted in supports 162 by a pin 163 is urged inwardly by a spring 164 whereby one side of the plate 154 snaps into a notch 165. By this means the post and shoe are retained in an upwardly extended position and when it is desired to lower

the shoe the latch 161 is actuated by placing a foot on a projection 166 extended from the outer edge thereof.

The post 17 is resiliently supported from the lower end of the tube 150 with springs 167 and 168 on rods 169 and 170, respectively, the rods extending through a bar 171 on the lower end of the tube 150 and also through the ends of a bar 172 on the post 17. The upper ends of the rods are provided with heads 173 and 174 and the lower ends with nuts 175 and 176, respectively whereby tension on the springs may be adjusted.

The front or cover plate 136 is provided with an extension 177 that extends to the web 147 and the extension is provided with a knob 178 for adjusting the temperature of the shoe of the ironer and also a knob 179 for actuating a switch to turn the circuit of the rotor on and off.

It will be understood that a conventional shoe or buck may be used in combination with the roll 10; however, as illustrated in Figs. 13 and 14, the shoe 13 is provided with a cover plate 180 having an insulating liner 181 and the cover is secured to the shoe with screws 182. The shoe is provided with end sections 183 and 184 in which the heating elements, which in the design shown, are in the form of coils are wrapped around tubular insulating rods 186 and 187 and the coils are connected to a brass rod 188 at the center. The rod 188 is also supported in the end members 183 and 184 with tubular insulating members 189. By this means the temperature of the shoe may be regulated as desired.

The shoe 13 is suspended from the arm 18 on the upper end of the post 17 with studs 190, the lower ends of which are connected to a base plate 191 that is connected to the cover plate 180 with screws 192 and, as shown in Fig. 13, the studs 190 extend through hubs 193 on the end of the arm 18 and the threaded upper ends of the studs are provided with adjusting nuts 194. Springs 195 are positioned between the lower surface of the arm 18 and shoe.

Figure 22 illustrates a typical connection of a wire of an electric circuit to the electric heating element through the cover plate 180, the cover plate being provided with a threaded plug 196, of insulating material and the plug having a stud 197 secured therein. The lower end of the stud 197 provides a terminal 198 for a wire 199, and a connector 200 on the wire by a screw secured against a nut 201 on the end of the stud. The stud is also provided with a projection 202 to prevent the stud rotating as connections are made thereto and the upper end of the stud is provided with a threaded section 203 on which a nut 204, of insulating material, is threaded. A wire 205 extends through an opening 206 in the upper end of the nut and the end of the wire is secured to the end of the stud 197 by soldering or other suitable means.

As shown in the wiring diagram shown in Fig. 2 the knob 179 actuates a switch 207 one terminal of which is connected by a wire 208 to a source of current supply with the wire being connected to terminals of the motor 75 and the other terminal of the switch 207 being connected by a wire 209 to the other side of the source of current supply. The wire 209 is also connected by a wire 210 to one of the terminals, such as the terminal shown in Fig. 22, of the electric heating element and the other terminal of the electric heating element is connected by a wire 211 to a resistance coil 212 of a rheostat or regulator 213. The opposite terminal of the control device 213 is connected by a wire 214 to the wire 208. It will be understood, however, that current may be supplied to the ironer by other suitable means.

As illustrated in Figs. 20 and 21 the shaft 72 may be rotated with a wheel or lever, as indicated by the numeral 101, and the wheel may be provided with points 215, 216, and 217 to correspond with high points of the

cams, the high points being indicated in the diagram shown in Fig. 20.

With the machine designed and assembled in this manner three separate and distinct movements are accomplished such as an oscillating movement with the roller rotating first in one direction and then in the other across or below the shoe or buck; a continuous rotary motion with the cylinder rotating continuously in the same direction; and third, a longitudinal reciprocating motion with the roller sliding longitudinally on the shaft and under the shoe.

By this means substantially all types of garments and other articles may be rapidly ironed on the machine, and in ironing difficult articles the operator may readily shift from one motion to another.

All bearings are provided with grease cups or fittings and as shown in Figure 2, threaded openings 3 are provided in the frame for grease cups.

It will be understood that modifications, within the scope of the appended claim, may be made in the design and arrangement of parts without departing from the spirit of the invention.

What is claimed is:

In an ironing machine, a housing including a horizontally disposed base, wheels for supporting said housing, a roller, a spindle supporting said roller, a sleeve slidably mounted on said spindle, a spring pressed shoe having an arcuate lower surface and said shoe having electric heating elements therein, manually operable means for adjusting the temperature of the shoe, a post having an arm extending outwardly therefrom, said shoe being secured to said arm, a foot plate extending forwardly from said post so that the plate is within reach of a foot of the operator whereby the shoe may be held downwardly upon the roller, a foot crank for elevating said shoe, a latch for selectively retaining the shoe in a raised position, a cover on said roller, said roller further including a cylindrical casing, a lever having its upper end connected to said sleeve, a projection on the lower end of said lever, a frame supported within said housing and including vertically disposed members, a first shaft jour-

naled in said vertically disposed members, a first cam mounted on said shaft and provided with a groove for receiving said projection whereby upon rotation of the cam, the projection will follow the groove so that the lever will move the roller longitudinally of the spindle, a sleeve for supporting said cam, a spring pressed clutch connected to said last named sleeve, a U-shaped bracket secured to said frame, a guide bar connected to said lever and extending through said bracket, there being an opening in the end wall of said housing for the projection therethrough of said guide bar, a yoke for actuating said clutch, a slider connected to said yoke and having a projection extending therethrough, a member for slidably supporting said slider, a second cam mounted on said 15 second shaft and having a groove for receiving said last named projection, a motor positioned within said housing, belt and pulley means connecting said motor to said first shaft, chain and sprocket means connecting said first shaft to said spindle, a clutch for controlling rotation 20 of said spindle, a yoke for actuating said last named clutch, a slider connected to said last named yoke and having a projection extending therefrom, a third shaft positioned in said housing and having a third cam thereon and said third cam being provided with a groove for receiving said last named projection, chain and sprocket means connecting said second and third shafts together, an index mounted on the extended end of said second shaft, an indicator for coaction with said index, a fourth cam mounted on said third shaft, a clutch actuated by 25 said fourth cam for oscillating said spindle, said housing further including a rear plate and a front plate, and a hingedly mounted door connected to said front plate.
